Primary Examiner — Michael A. Pratt*(74) Attorney, Agent, or Firm* — Lori Sandman, Esq.(57) **CLAIM**

The ornamental design for a torque tool, as shown and described.

DESCRIPTION

FIG. 1 is a perspective view of the torque tool of this invention;

FIG. 2 is a perspective view thereof, opposite the end shown in FIG. 1;

FIG. 3 is a sectional view thereof, showing the interior structure of one half of the tool, where both halves are identical;

FIG. 4 is a side view thereof;

FIG. 5 is a bottom view thereof;

FIG. 6 is a top view thereof;

FIG. 7 is a perspective view thereof engaged with a fastener or component in the recess of the tool, said fastener or component is provided for context and forms no part of the invention;

FIG. 8 is a perspective view thereof engaged with a differently configured component in the recess of the tool than is shown in FIG. 7, said component is provided for context and forms no part of the invention;

FIG. 9 is a perspective view thereof engaged with a wing nut in the recess, said wing nut is provided for context and forms no part of the invention; and,

FIG. 10 is a perspective view thereof engaged with a wing nut and coupled with a wrench to extend torque capacity, said wing nut and said wrench are provided for context and form no part of the invention.
